UNITED STATES PATENT OFFICE.

THOMAS G. GOODFELLOW, OF CHICAGO, ILLINOIS.

COAL-ELEVATOR.

SPECIFICATION forming part of Letters Patent No. 374,895, dated December 13, 1887.

Application filed March 31, 1887. Serial No. 233,218. (No model.)

To all whom it may concern:

Be it known that I, THOMAS G. GOODFELLOW, a citizen of the United States, residing at Chicago, in the county of Cook and State of Illinois, have invented a certain new and useful Improvement in Coal-Elevators, which is fully set forth in the following specification, reference being had to the accompanying drawings, in which—

10 Figure 1 is a vertical sectional view of an apparatus embodying my invention; Fig. 2, a plan section taken on the line 1 1 of Fig. 1; Fig. 3, a detail sectional view taken on the line 2 2 of Fig. 1; Fig. 4, a detail sectional view taken on the line 3 3 of Fig. 3 and on an enlarged scale; Fig. 5, a detail view of a portion of the locking mechanism detached and on a still larger scale, and Fig. 6 a detail view illustrating the tripping projections.

20 Like letters refer to like parts in all the figures of the drawings.

My invention relates to elevators for domestic use, it being designed more particularly for elevating coal, although its application is 25 of course not limited to this particular use; and it has for its object to provide an elevator which may be loaded, hoisted to any predetermined point of its travel, and automatically unloaded to said point by a single attendant 30 at the bottom of the elevator-shaft.

To these ends my invention consists in certain novel features which I will now proceed to describe, and will then particularly point out in the claims.

35 A represents the car or bucket, which may be operated by any suitable hoisting mechanism. That which I prefer for the purpose is that shown in the drawings, in which the car or bucket is mounted in a frame, B, moving 40 in suitable ways, C, and having attached to it at top and bottom a sprocket-chain, D, which passes over a sprocket-wheel, E, at the top of the elevator-shaft and over a similar wheel, E', at the bottom of said shaft, said chain being also provided with a counterbalance-weight, d, to act as a counterpoise for the car or bucket A. On the shaft e of the lower sprocket-wheel, E', is mounted a sprocket-wheel, e', over which a sprocket-chain, e'', 45 passes to a sprocket-wheel, E'', of smaller diameter, the shaft of which is provided with a

crank-handle, E³, by means of which the apparatus is operated. A ratchet-wheel, F, on the shaft e serves, in conjunction with a pawl, f, capable of engagement or disengagement therewith in the usual manner, to prevent or 55 permit the descent of the car or bucket A.

Power applied to the crank-handle E³ will rotate the sprocket-wheel E² on the shaft thereof, and, through the medium of the sprocket-chain e'', impart a rotary motion to the sprocket-wheel e' and its shaft e. The sprocket-wheel E' on this shaft will then move the sprocket-chain D, and consequently the car or bucket A, in the desired direction, either 60 up or down. This mechanism is in common use and is not of my invention, and it therefore needs no extended description here, as any approved apparatus for the purpose may be substituted therefor, my present invention 65 not relating to the hoisting apparatus. The ratchet F and pawl f are common in machines of this description and operate in the usual manner.

The car or bucket A is provided with sides 75 a and a forward and downward inclined bottom, a', being closed at the front by a door, a², hinged at the top to swing outward, and bearing, when closed, against a rabbet, a³, in the bottom a', said door and rabbet being preferably arranged some little distance back from the front of the car, so as to prevent the door from catching upon the side of the elevator-shaft when it swings out. A space, A', is 80 thus formed at the rear of the car to receive the load to be carried, the open front part, A², of the car forming a discharge guide or spout for the same.

The top of the car A is covered by a suitable deck or flooring, A³, the rear portion, a⁴, 90 of which is hinged, and may be raised to give access to the interior of the space A² when the door a² is closed.

G represents a dog or catch secured to the rear of the door a² at the bottom thereof and 95 extending rearward through a suitable slot or aperture in the rabbeted wall a³ of the bottom a' of the car A. This dog is provided with a suitably beveled and shouldered head, g, for engagement with the locking bolt.

H represents the locking-bolt, provided 100 with a lug, h, for engaging with the dog G,

and mounted to slide longitudinally in suitable bearings, h' , on the rear of the part a^3 , being normally thrust outward in the direction of the tripping projections hereinafter described by means of a suitable spring. In the construction shown a spiral spring, H' , is employed, surrounding the body of the locking-bolt H and bearing against a collar, h^2 , thereon at one end, the other end of said spring abutting against one of the bearings h' , as shown.

I represents a sleeve adjustably mounted on the outer end of the bolt H , its adjustment being preferably obtained by forming in the said sleeve a slot, i , provided with lateral recesses i' , corresponding in number to the number of stations or floors to be served by the elevator and corresponding in location or distance from each other to the size of the corresponding series of tripping projections. A pin, H^2 , on the locking-bolt H serves, in conjunction with the slot i and recesses i' , to lock the sleeve I on said bolt, and a spring, I', bearing against the collar h^2 and against the inner end of the sleeve, serves to thrust the sleeve normally outward when not locked.

J represents a tripping arm or lever pivoted to the car A and provided with a slot, j , by means of which it is connected to the sleeve I, the threaded end I^2 of which passes through the said slot and receives a nut, i^2 , on the outside. The end J' of the tripping-arm is bent outward, so as to engage with the tripping projections. This tripping-arm may be dispensed with, and the sleeve I extended sufficiently to perform its functions; but I prefer to employ the construction shown.

K, K', and K² represent a series of tripping projections mounted, preferably, on one of the ways C in the line of travel of the tripping-arm J. These tripping-arms are located each in proper relation to its corresponding floor or station L, L', &c., so that when the car is in position to discharge at said floor or station, either upon the floor itself or into a suitable receptacle, M, placed thereon, the tripping-lever is in such relative position to said tripping projection that its end J' is in line with the center or most prominent part of the same. The said series of projections increase in size in ascending, the lower one, K, being of such size that when the sleeve is adjusted to its outermost position, with the pin H^2 in the innermost recess i' , the tripping-lever will engage with the said projection. The next projection, K', corresponds with the next recess i' , and so on in ascending, any desired number of stations or floors being served each with a projection more prominent than the one below and less prominent than the one above, and a corresponding series of recesses i' being of course employed in the sleeve I, so that when the sleeve is set to trip at a given floor or station the tripping-arm will clear all of the tripping projections below the one for which it is set, and will be operated by the said projection for which it is set.

The operation of my improved elevator will be readily understood from the preceding description, and is as follows: It being desired, for instance, to raise coal or the like from the basement to any given floor, the door a^2 is closed, the space A' filled, and the hinged top a^3 closed, and the sleeve I set for the desired floor. By means of power applied to the crank-handle E² the car A will be raised, the tripping-arm J clearing all the tripping projections until it reaches the one for which it is set. The said projection will force the arm and sleeve inward, carrying the bolt H with it, until the projection h on said bolt is clear of the dog g, when the weight of the coal in the space A' will swing open the door a^2 , and the coal will be discharged at the proper point, being guided by means of the front portion, A², to its place of deposit. The door a^2 will swing back and close automatically, the spring H' locking the same by engaging the projection h on the bolt H with the dog G, and the car may be lowered for another load for the same or another floor or station. In case the door a^2 does not close, it will be protected from damage by catching on anything during the descent of the car, owing to its location within the part A² of the car. The top A³ of the car will serve to carry groceries, passengers, or the like, after the manner of an ordinary dumb-waiter or elevator, and when used for this purpose the elevator may travel the entire length of its shaft regardless of the position in which the sleeve I is set, since the bolt will yield sufficiently to pass over any of the tripping projections.

It is obvious that various modifications in the details of construction may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. In an elevator for coal, &c., the car or bucket provided with an inclined bottom and closed at the front by a door hinged at its top to swing outward, in combination with a locking-bolt, an adjustable tripping device on said bolt, and a series of tripping projections of increasing size, one for each floor or station, to operate the tripping device, substantially as and for the purposes specified.

2. In an elevator for coal, &c., the car or bucket provided with the inclined bottom a' , having rabbet a^3 , and the door a^2 , hinged at its top to swing outward and resting normally against said rabbet, the said door being arranged within the car back from its front edge, and forming, in conjunction with the body-walls of the car, the rear space, A', and front space, A², substantially as and for the purposes specified.

3. In an elevator for coal, &c., the car or

bucket A, provided with side walls, a , inclined bottom a' , and top or deck A³, having top door, a^2 , at the rear, in combination with the door a^2 , hinged at its top to swing outward within 5 the car or bucket, and forming, in conjunction

with the other parts enumerated, the front space, A², and rear space, A', substantially as and for the purposes specified.

4. In an elevator for coal, &c., the car or 10 bucket A, having door a^2 , provided with dog or catch G, the spring locking-bolt H, having lug h, the sleeve I, adjustable upon said locking-bolt, and a series of tripping projections, K K' K², of increasing size, substantially as 15 and for the purposes specified.

5. In an elevator for coal, &c., the combination, with the car, its door, and the spring locking-bolt provided with pin H², of the sleeve

I, mounted on said bolt and having slot i, with lateral recesses i', and a series of tripping projections, K K' K², corresponding to the said lateral recesses, substantially as and for the purposes specified. 20

6. In an elevator, the combination, with the car, its door, and the spring locking-bolt, of 25 the sleeve adjustable upon said bolt, the tripping-arm pivoted to the car and connected to the sleeve, and the series of tripping projections of increasing size arranged in the path of said tripping-arm, substantially as and for 30 the purposes specified.

THOMAS G. GOODFELLOW.
